(57) **CLAIM**

The ornamental design for a rosary, as shown and described.

DESCRIPTION

FIG. 1 is a front perspective view of a rosary showing my new design;

FIG. 2 is a left side view thereof.

FIG. 3 is a top view thereof.

FIG. 4 is a front perspective view of a second embodiment of a rosary showing my new design;

FIG. 5 is a right side view of the alternate design; and,

FIG. 6 is a top view of the alternate design.

The rear views are not shown, as they are flat and unornamented, and form no part of the claimed design.

1 Claim, 2 Drawing Sheets
